UNITED STATES PATENT OFFICE.

JAMES ARTHUR THOMPSON, OF RUSHVILLE, ILLINOIS.

WRENCH.

Application filed February 9, 1922. Serial No. 535,142.

To all whom it may concern:

Be it known that I, JAMES ARTHUR THOMPSON, a citizen of the United States, residing at Rushville, in the county of Schuyler and State of Illinois, have invented a new and useful Improvement in Wrenches, of which the following is a specification.

My present invention relates to improvement in wrenches, and besides involving an extension of the ratchet principle described in my prior Letters Patent Number 1,413,243, involves instrumentalities which are capable of assembly to provide a brace in which the tool holding element may be adjusted at any angles with respect to the plane of the brace, and the brace may be employed either with or without the ratchet, and as a direct drive tool, or in connection with the handgrip of the brace as a tool in which the tool holding element will be speeded up to revolve at a different and greater speed than the brace. It will also be seen that the brace may be disassembled so as to economize space in package and transportation, and while disassembled the tool holding element and the arm which carries the same may be advantageously employed with or without the ratchet as a wrench for either starting a nut or more quickly screwing the nut or bolt off or on, as may be desired. It will also be seen that my tool can be adjusted in many different ways in order to make it available for use in restricted locations. I have also shown modified structures for securing simple wrenches involving some of the principles in which the speed of rotation of the tool holder is increased over the speed of the ordinary rotation of the wrench handle.

I prefer to accomplish the before mentioned objects by means of the structures illustrated in the accompanying drawing in which—

Fig. 1 is a side elevation, mostly in section, of a brace embodying my present invention.

Fig. 2 is a section on line 2—2, Fig. 1, showing the manner of assembly of the breast arm.

Fig. 3 is a section on line 3—3, Fig. 1, showing the manner of assembly and swiveling of the tool holding arm;

Fig. 4 is a section on line 4—4, Fig. 1, showing a portion of the ratchet elements.

Fig. 5 is a fragmental detail of a modified

arrangement for increasing the speed of revolution of the tool holding element.

Fig. 6 is a bottom plan and section on line 6—6, Fig. 5, and

Fig. 7 is a side elevation of a modified form of wrench also involving provisions for increasing the speed of the tool holding elements.

Fig. 8 is a transverse section on line 8—8, Fig. 4.

Similar reference characters refer to similar parts where the same are illustrated in the respective views.

The tool holding element 10 is generally similar to the tool holding element described in my before referred to application, and consists of a cylinder with a central angular, preferably hexagonal, channel 11 therein, the end of which channel is enlarged, at 12, to accommodate the plug end of a larger tool. At a suitable distance from the end having the enlarged socket the exterior of the cylinder is reduced to provide a shoulder 13, and in the central area of the reduced portion are milled slots to provide ratchet teeth 14 therebetween. The reduced portion of the tool holding cylinder is journaled in a collar 15, and on the portion of the cylinder which extends beyond the journal is fixedly mounted in any suitable manner a bevel-gear 16. The entire assembly, as thus described, is held together by a split ring 17 snapped into an annular groove 18 upon the exterior adjacent end of the tool holding cylinder.

The collar 15 which forms the journal for the tool holding cylinder is either mounted on or constitutes a portion of a tube 19 the central bore of which latter communicates with the inside of the collar or journal. Mounted within the bore of tube 19 are ratchet dogs or pawls 20 and 21, similar to the dogs described in my before mentioned application, except that the spring 22 for exerting tension upon the dogs, instead of being seated in a socket in the bore, surrounds a rod 23 and engages a pin 31 which secures rod 23 to dog 21. The rod 23 extends to and beyond the end of tube 19 where it passes through a disk 24 mounted in the end of said tube 19 and upon its outer end is provided with a knob 25. Between disk 24 and a washer 26 secured upon rod 23 is a spiral spring 27 which keeps rod 23 in its innermost

position and the dogs pressed towards the ratchet teeth. It will now be seen that by drawing rod 23 outwardly from within tube 19 ratchet dogs 20 and 21 will be withdrawn from engagement with the ratchet teeth 14 when they can then be rotated by rod 23 a half turn to reverse the action of the ratchet, or a quarter turn to dispose the dogs at right angles to the ratchet-teeth in which position they will be inoperative as a ratchet. They will be held in their inoperative position by means of opposite longitudinal slots 19^a in the bore of tube 19 into which slots the extended ends of pin 31 project, except when the dogs are withdrawn from engagement with the ratchet and swung at an angle thereto in which position the extended ends of pin 31 will engage shoulder 19^b in the bore of tube 19.

To obviate the necessity of referring to my before mentioned application, it should be noted that the dogs or pawls 20 and 21 are longitudinal sections of a cylinder, the dog 21 being preferably longer than dog 20 and having one portion thereof cut away for the reception of dog 20, the elongated end of said dog 21 being a complete cylinder and having a longitudinal bore 28 for the reception of the spring 22 heretofore mentioned, and through which pin 31 passes. The dog 20 is longitudinally slotted, as at 29, and a transverse pin 30 mounted in dog 21 extends into slot 20 and insures the simultaneous withdrawal and rotation of both dogs and permits a limited longitudinal independent movement of said dogs. The face of slot 29 is cut away to accommodate the laterally flattened head 30^a of the end of pin 30. This construction permits the assembly of dogs 20 and 21 with the spring 22 and the securing of these parts together in desired adjustment before they are inserted in the bore of tube 19.

A pin 31 is disposed transversely of bore 28 past which the convolutions of spring 22 may be screwed to adjust the tension on dog 20; the pin 31 serving also to connect dog 21 with rod 23, as above mentioned. In the present form of my invention, in order to prevent a rotation of spring 22 with respect to the dogs when in use and when the dogs are rotated by means of rod 23, I have turned the forward end of spring 22 longitudinally to abut the inner longitudinal face of dog 20, as clearly shown in Fig. 4.

Revolutely mounted about tube 19 is a sleeve 32 on one end of which is a bevel gear 33 meshing with gear 16 heretofore mentioned. On the opposite end of sleeve 32 is another bevel gear 34 meshing with a bevel gear on a hand grip to be hereinafter described. The tube 19 is secured in the collar 36, to prevent its accidental withdrawal therefrom during the adjustments

to be hereinafter described, by means of an annular groove 19^a around the end of said tube into which is snapped a split ring 19^d. The end of the tube 19 opposite that carrying collar 15 is transversely bored to provide tapered recesses or sockets 35 and this recessed end of the tube is journaled in a collar 36 somewhat similar to collar 15, which also is secured to or forms a portion of a tubular member 37 in the bore of which is a longitudinally movable rod 38 the inner end of which is tapered to tightly engage the recesses or sockets 35. The rod 38 extends through a disk 39 secured in the opposite end of tubular member 37, and is provided with a knob 40, a washer 41 and a spring 42, similar in construction and operation to the corresponding parts on rod 23, and its opposite end is guided in a preferably reduced portion 43 of the bore of the tubular member 37. As seen, recesses or sockets 35 and the end of rod 38 engaged therewith are tapered so as to insure a snug fit and avoid lateral play or movement when the parts are locked together in any of their adjusted positions.

Surrounding tubular member 37 is a hollow cylindrical shell or hand-grasp 44 that is spaced from the tubular member at its lower end by a ring or annulus 45, and at its upper end by a bored frustro-conical shaped block 46, said ring and block adapted to rotate freely upon tubular member 37 and to be moved longitudinally thereon. Bevel gear teeth 47 project from the tapered face of block 46 that are adapted to mesh with bevel gear 34 on the adjacent end of sleeve 32 heretofore mentioned, and shell 44 is secured to the elements that space it from the tubular member 37 by bending the end edges of the cylinder, which is preferably sheet metal, laterally upon the angular portions of said spacing elements, as seen in Fig. 1 of the drawings.

As shown in the drawings, hand-grasp 44 is in its uppermost position so that the gear teeth carried thereon are in mesh with gear 34, but it is desirable when greater power is required to disengage these gears and to do this the shell 44 is moved longitudinally from gear 34 to disengage these gears. In order to retain shell 44 in either of its desired positions I have provided a spring pressed ball 48 that is seated in a socket 49 in the portion of the tubular member having the reduced bore 43 so that the ball will retain the handgrip with the gears 34 and 47 engaged or disengaged. A plurality of balls arranged about member 37 may be employed if desired.

The end of tubular member 37 opposite collar 36 is fitted into a sleeve 50 disposed transversely upon the end of an internally threaded socket-piece 51, and said tubular member 37 is provided with a tapered re-

cess or aperture 52 that is adapted when assembled to be brought into registry with the inner end of the threaded bore of the socket-piece 51. A substantially L-shaped breast arm has its shorter arm 53 positioned in axial alignment or parallel with the normal position of the axis of the tool holder block 10, and provided with a rotatable head 54, and the longer arm 55, which is at substantially a right-angle to shorter arm 53, has its opposite end portion provided with screw-threads 56 and is screwed into the threaded bore of socket piece 51. At its extreme end arm 55 is tapered, as at 57, so as to wedge into a tapered recess 52 on the adjacent end of tubular member 37 and also has its end face concaved, as at 58, to conform with the interior face of the bore in said tubular member. In order to secure the parts against accidental rotation after assembly I insert a pin 59 transversely through the central portion of socket piece 51 and through a longitudinally elongated transverse slot 60 in the threaded portion 25 of arm 55 of the breast arm.

From the foregoing, it will be seen that, assuming the elements of the structure to be in the relative positions shown in Fig. 1, and it is desired to use the tool for the purpose of tightening a nut or an angular bolt head, the tool is positioned in the manner of an ordinary brace so that by rotating the whole structure by means of the handgrasp or shell 44 the tool holder will be speeded to two revolutions to each single revolution of the brace, provided the gears are equal toothed, as shown. Also the brace may be held stationary and shell 44 rotated upon tubular element 37, which will cause a rotation of sleeve 32 through the medium of gears 34 and 47, and gear 33 on the opposite end of sleeve 32 will actuate gear 16 on the tool holder 10 and rotate the latter without disturbing the position of the brace elements. If the hand grip is moved to disengage its gear no speeded motion of the tool holder will be secured, but with the dogs 20 and 21 in engagement increased power is available for either starting or setting up a nut or bolt. By changing the relative positions of dogs or pawls 20 and 21, the brace may be operated in the manner of a ratchet brace in the ordinary way, in both a forward or reverse direction. Also, by withdrawing rod 38 from one of sockets 35 and rotating tube 19 upon its axis an angular adjustment and positioning of the tool holding bores in holder 10 may be secured. As previously stated, the handle grip or shell 44 may be reciprocated longitudinally upon tubular member 37 to disengage gears 34 and 47, and when this is done the brace may be operated in the manner of an ordinary brace; or, sleeve 32 may be rotated upon tube 19 to "spin" a

nut or angular bolt head prior to tightening or after loosening the same. The tube 19 with tool holder 10 and sleeve 32 may be used independently of the other portions of the brace structure and by partially withdrawing the sleeve on tube 19 the leverage may be materially increased.

In the structure disclosed in Figs. 5 and 6 the four bevel gears 16, 33, 34 and 47, together with sleeve 32 are omitted, and in lieu thereof I have employed a chain and sprocket arrangement for "speeding" the rotation of tool holder block 10. The bore 11 in this structure does not extend through block 10 and the end of said block opposite socket 12 is reduced to provide an extension 41 upon which a sprocket 62 is secured by means of a nut 63 so as to rotate therewith. Upon an intermediate portion of tube 19, preferably adjacent collar 36, I position a lateral stud 64 that provides an arbor or journal for another sprocket 65 in alignment with sprocket 62, and said sprockets are connected by a suitable chain 66 so that the rotative movement of sprocket 65 may be transmitted to sprocket 62. Preferably cast integral with the hub or other convenient portion of sprocket 65, or rigidly pinned thereto, is a spur-gear 67 that journals upon the outer portion of stud 64. In place of the frustum-conical block 46 employed on the tubular member 37 (Fig. 1), I employ block 68, shown in Figs. 5 and 6, to which handgrasp shell 44 is secured, and upon the outer portion of said block is a spur-gear 69 that is in mesh with spur-gear 67. The operation of this modified structure for a brace is substantially the same as that described in the preferred form so far as the speeding of the tool holding block, but owing to the difference in the transmission elements the axial rotation of tube 19 for adjusting the angularity of the tool holding block cannot be had, and, hence the reciprocable rod 38 is utilized for the purpose of removably securing tube 19 in collar 36.

It will be understood that the "speeding" functions of the two structures heretofore described may be applied to an ordinary wrench, and for the purpose of a convenient disclosure of this application of the principles I have illustrated the same in connection with the ratchet wrench or tool shown in my before mentioned patent. The body 70 of the wrench is of irregular shape and upon one end is the collar 15 having a bore transverse to the axis of the main longitudinal portion of the body, in which collar is mounted the tool holding block 10 having ratchet teeth 14. The pawls or dogs 20 and 21 and the tension spring 22 are slidably and rotatably mounted in a suitably bored recess 71 upon body 70 of the wrench and extending back thereon from collar 15, and

the transverse pin 30 extends from dog 21 through slot 29 in dog 20 and through a bayonet slot 73 in the embossment, and its outer end provided with a head 73a. The operating rod 23 is therefore discarded in this type. The end of the tool holding block opposite angular socket 12 extends through collar 15 where it is provided with the annular groove 18 and split ring 17, as shown in the type 10 disclosed in Fig. 1. Between split ring 17 and the adjacent portion of collar 15, the sprocket 62, similar to that shown in Fig. 5, is secured by means of a removable transverse pin 74. Intermediate the ends of body 15 70, preferably adjacent the bent portion, lateral stud 64 is secured upon which is journaled sprocket 65 and said sprocket is operatively connected to sprocket 62 by the chain 66. For the purpose of permitting a 20 rotation of the tool holding block 10 independently of the movement of tool body 70, I have provided a headed embossment 75 upon the hub or other portion of sprocket 65 so that by rotating said embossment sprocket 25 65 will rotate tool holding block 10 through the instrumentality of chain 66 and sprocket 62.

When the pawls or dogs 20 and 21 are in their desired adjusted positions, the device 30 may be used in the manner of an ordinary wrench, or by adjusting the pawls with relation to teeth 14 the wrench may be used like a ratchet tool to loosen or tighten a nut or bolt head in an inconvenient location, and 35 after loosening the element the nut or bolt may be speeded off in the same manner as with the other types of tools herein described. The wrench may be also employed to speed on a nut or headed bolt by means of 40 the headed embossment 75 and then tightened into place by the wrench handle, as will be understood.

I have herein illustrated and described three of the preferred embodiments of my 45 invention, but it will be obvious that other structures may be utilized which embody the generic principles herein disclosed, and I therefore desire it understood that such changes are contemplated within the scope 50 of the appended claims.

What I claim:

1. A tool comprising a socketed member, an arm with respect to which said socketed member is transversely journaled, a second 55 arm with respect to which said first mentioned arm is transversely journaled and rotatable upon its axis, a latch for adjustably securing said arms in any desired relative position, a right angled arm extending 60 from said second arm, and a knob revolvably mounted on the extended end of said right angled arm.

2. A tool comprising a socketed exteriorly toothed cylindrical member, a tubular member 65 having a transverse collar at one end in

which said cylindrical member is journaled, ratchet detents mounted within said tubular member and co-acting with the teeth on said cylindrical member, a rod extending from the remote end of said tubular member for throwing said ratchet detents into and out of action and reversing their direction, a second tubular member having a transverse collar at one end in which said first mentioned tubular member is revolvably mounted, a rod carried by said second tubular member and co-acting with said first mentioned tubular member within the collar, and an angular breast arm secured to the remote end of said second tubular member. 70

3. A wrench comprising a tool holding member, an arm in which said member is rotatably mounted, a ratchet element carried by said arm and engageable with said member, a second arm in which said first arm is 85 rotatably mounted, means for securing said arms in divers positions with respect to each other, a sleeve rotatably mounted on said second arm, and means mounted on said first arm for transmitting the rotative movement 90 of said sleeve to said tool holding member.

4. A wrench comprising a tool holding member having exterior teeth, an arm in which said member is rotatably mounted, a ratchet detent carried by said arm and co-acting with said teeth, a rod extending to the exterior of said arm for positioning said detent, a second arm in which said first arm is rotatably mounted, means for latching said arms with respect to each other, a sleeve 95 mounted on said second arm and movable longitudinally and concentrically with relation thereto, means carried by said first arm for rotating said tool holding member, and devices mounted on said sleeve and adapted to be brought into coaction by the longitudinal movement of said sleeve with the rotative means mounted on said first arm. 100

5. A wrench comprising a tool holding member having exterior teeth, an arm in which said member is rotatably mounted, a ratchet detent carried by said arm and co-acting with said teeth, a rod extending to the exterior of said arm for positioning said detent, a second arm in which said first arm is rotatably mounted, means for latching said arms with respect to each other, a sleeve mounted on said second arm and movable longitudinally and concentrically with relation thereto, means carried by said first arm for rotating said tool holding member, and devices mounted on said sleeve and adapted to be brought into co-action by the longitudinal movement of said sleeve with the rotative means mounted on said first arm, 115 and elements for holding said sleeve in and out of engagement with said means. 120

6. A wrench comprising a tool holding member having exterior teeth, an arm in which said member is rotatably mounted, a 125

- ratchet detent carried by said arm and co-acting with said teeth, a rod extending to the exterior of said arm for positioning said detent, a second arm in which said first arm is rotatably mounted, means for latching said arms with respect to each other, a sleeve mounted on said second arm and movable longitudinally and concentrically with relation thereto, means carried by said first 5 arm for rotating said tool holding member, devices mounted on said sleeve and adapted to be brought into coaction by the longitudinal movement of said sleeve with the rotative means mounted on said first arm, 10 elements for holding said sleeve in and out of engagement with said means, and a right-angle breast arm removably secured to said second arm.
7. In a tool, a breast arm, a handle member 20 detachably secured to one end thereof, a sleeve longitudinally and revolvably movable upon said handle, a laterally extending arm rotatively and detachably mounted in the opposite end of said handle member, a retractable latch element carried by said handle member and engageable with said lateral arm for securing said handle member and lateral arm in adjusted positions; said arm provided with means to receive said 25 latch element, a tool holder journaled in the extended end of said lateral arm, and means in disengageable relation with said sleeve for rotating said tool holder.
8. A tool comprising a socketed exteriorly toothed cylinder, a member having a transverse collar at one end in which said cylinder is journaled, ratchet detents mounted with said member and coacting with the teeth on said cylinder, means for throwing said 30 ratchet detents into and out of action and reversing their direction, a second member having a transverse collar at one end in which said first mentioned member is rotatably mounted, means coacting with said first mentioned member within said last mentioned collar whereby said first and second members are secured in divers adjusted positions, and an angular breast arm carried by the remote end of said second member.
- 35 9. A brace comprising a substantially U-shaped structure, a holder rotatably mounted in the outer end of one of the arms thereof, means permitting the transverse adjustment of said holder with respect to the axis of the 40 arm in which the same is mounted, a sleeve rotatable upon the member connecting the arms of said structure, toothed members upon said sleeve and said holder, and devices operatively connecting said toothed members whereby said holder may be actuated by the rotation of said sleeve.
10. A brace comprising a substantially U-shaped structure; one of the parallel arms of said U-shaped structure being detachable 45 therefrom and arranged to be adjusted to any desired angle thereto, and means for latching said arm in adjusted positions.
11. A brace comprising a substantially U-shaped structure, one of the arms of said 50 structure being detachably mounted thereon and rotatably upon its own axis independent of the other structure, means for latching said arm in adjusted positions, a rotatable tool holder journaled transversely in the 55 outer end of said arm, a pawl and ratchet connection between said holder and said arm, a sleeve on the member connecting the arms of said structure, and devices operatively connecting said sleeve and said 60 rotatable element.
12. A brace comprising a cylinder, an arm in one end of which said cylinder is transversely journaled, a pawl and ratchet connection between said cylinder and arm, a 65 second arm extending laterally of said first arm in which the latter is adjustably mounted, a rotatable sleeve surrounding said first arm, beveled gear connection between said sleeve and said cylinder whereby the 70 latter may be adjusted to divers angles with respect to its arm without disengagement of the gear connection, a rotatable sleeve surrounding said second arm, beveled gear connection between said first and second sleeves, and an angular arm with which said second 75 arm forms a crank for actuating the brace.

Signed at Chicago, county of Cook, and State of Illinois, this 4th day of February, 1922.

JAMES ARTHUR THOMPSON.
